UNITED STATES PATENT OFFICE

152,970

DESIGN FOR A YO-YO TOY

Richard V. Hirsch, South Gate, Calif.

Application June 23, 1947, Serial No. 139,873

Term of patent 7 years

(Cl. D34—15)

To all whom it may concern:

Be it known that I, Richard V. Hirsch, a citizen of the United States of America, and a resident of the city of South Gate, in the county of Los Angeles and State of California, have invented a new, original, and ornamental Design for Yo-Yo Toy, of which the following is a specification, reference being had to the accompanying drawings, forming a part thereof.

In the drawings:

Figure 1 is an end elevational view of a Yo-Yo toy, showing my new design,

Figure 2 is a side elevational view thereof, and Figure 3 is an inner side elevational view.

The Yo-Yo toy is transparent.

This application is a continuation-in-part of

application Ser. No. D. 124,746, filed December 14, 1945, for "Toy," and now abandoned.

I claim:

The ornamental design for a Yo-Yo toy, substantially as shown and described.

RICHARD V. HIRSCH.
